SHOULDER STRAP FOR UNDERGARMENTS

John V. Hollar, Bridgeport, Conn., assignor to The
La Resista Corset Company, Bridgeport, Conn.,
a corporation of Connecticut

Application October 21, 1947, Serial No. 781,086

2 Claims. (Cl. 2—323)

1

The present invention relates to a shoulder strap structure for use with brassières, foundations, and similar ladies' undergarments, and has for an object to provide a pre-shaped shoulder strap which will fit smoothly upon the slope of the shoulder with substantially equal pressure at each of its edges.

Heretofore known shoulder straps are constructed of a straight strip of ribbon or similar material having inner and outer edges of equal length, so that when they are engaged upon the unequal length surfaces of sloping shoulders, the inner or high edge of each strap will press tightly into the flesh, while the outer or low edge will be either loosely engaged or out of contact. This condition applies especially to non-stretchable straps. In the case of elastic stretchable straps the edges will stretch to conform to the unequal length shoulder surface, but the inner or high edge will be stretched to a greater extent than the outer or low edge, and will consequently exert greater pressure than the outer or low edge.

It is proposed, according to the invention, to provide a shoulder strap having a pre-shaped form wherein the inner edge of the strap is of greater length than the outer edge, such greater length being predetermined so that the two edges substantially correspond to the unequal lengths of the sloping shoulder surfaces to be engaged thereby, with the advantageous result that the strap will comfortably conform to the slope of the shoulder with equal pressure at each of its edges.

With the above and other objects in view, an embodiment of the invention is shown in the accompanying drawing, and this embodiment will be hereinafter more fully described with reference thereto, and the invention will be finally pointed out in the claims.

In the drawings:

Fig. 1 is a perspective view from the front showing upon a figure a garment provided with shoulder straps according to the invention.

Fig. 2 is a similar view from the rear.

Fig. 3 is a plan view of a shoulder strap according to the invention in flattened position.

Fig. 4 is a front view showing the shoulder strap in shoulder engaging position, the dot-and-dash lines indicating the slope of the shoulder.

Fig. 5 is an outer edge view of the shoulder strap as seen in Fig. 4.

Fig. 6 is a view similar to Fig. 4 showing for comparison purposes the heretofore known shoulder strap having straight equal length edges.

Similar reference characters indicate corre-

sponding parts throughout the several figures of the drawing.

Referring to the drawings, the shoulder strap, according to the invention, is formed of any suitable material capable of maintaining a pre-shaped plan. While a non-stretchable material is preferred, it will be understood that elastic stretchable material may be advantageously employed. The strap, as shown in the illustrated exemplary embodiment of the invention, has a lower surface for engagement with the shoulder and an upper exposed surface and comprises straight front and back end portions 10 and 11 having straight, parallel inner and outer edges, 15 and an intermediate portion 12 of curved outline having concentrically curved inner and outer edges, its inner edge 13 being of relatively greater length than its outer edge 14, and the inner and outer straight edges of the end portions 10 and 11 being substantially tangential to the inner and outer curved edges 13 and 14. The curvature of the portion 12 is predetermined with respect to the slope of an average shoulder. It will thus be seen that when the strap is engaged over the shoulder, with the end portions 10 and 11 substantially vertically disposed, the intermediate portion 12 conforms to the slope of the shoulder with substantially equal pressure at its inner and outer edges, these edges being of substantially corresponding length to the unequal length surfaces of the shoulder engaged thereby. The strap will stay in position without being under tension. This is shown clearly in Fig. 4. In Fig. 6 there is shown, for comparison purposes, the manner in which the heretofore known shoulder strap engages a sloping shoulder. As the inner and outer edges are of equal length the inner edge fits tightly against the surface of the sloping shoulder, while the outer edge is raised therefrom. Obviously, when any strain is imposed thereon the inner edge will press into the flesh to a greater extent than the outer edge. Also, the strap must be under tension in order to retain its position upon the shoulder.

As shown in Figs. 1 and 2 the shoulder strap is incorporated in the garment in the usual manner, the front end portions 10 being connected to the front of the garment 15 by means of loop tabs 16, and the back end portions 11 being connected to the back of the garment by elastic tape members 17.

The shoulder strap may be produced in any suitable manner from any appropriate material, for instance, it may be woven or knitted to its pre-shaped form, it may be blanked or cut out

from suitable woven material in which case the edges will be biased to the weave of the material, or, it may be blanked, cut out, or molded from suitable composition or plastic material of a flexible nature. The material may either be non-stretchable or elastically stretchable to any desirable degree.

I have illustrated and described preferred and satisfactory embodiments of the invention, but it will be understood that changes may be made therein, within the spirit and scope thereof, as defined in the appended claims.

What is claimed is:

1. A shoulder strap for ladies' undergarments or the like, comprising a strip of flexible material having inner and outer edges and upper and lower surfaces and including a front end portion having equal length parallel inner and outer edges for attachment to the front upper edge of the garment, a rear end portion having equal length parallel inner and outer edges for attachment to the back upper edge of the garment, and an intermediate shoulder engaging portion substantially centrally of said front and rear end portion, the inner edge of said strip along said intermediate shoulder engaging portion being longer than the outer edge, whereby when said front and rear portions extend straight downwardly from said intermediate portion, their lower surfaces are substantially opposite and parallel to each other and said intermediate portion is transversely inclined between its inner and outer edges.

2. In combination, a ladies' undergarment hav-

ing front and back upper edges, and a pair of shoulder straps attached thereto, each comprising a strip of flexible material having inner and outer edges and upper and lower surfaces and including a front end portion having equal length parallel inner and outer edges attached to the front upper edge of the garment at one side of the center, a rear end portion having equal length parallel inner and outer edges attached to the back upper edge of the garment at one side of the center, and an intermediate shoulder engaging portion substantially centrally of said front and rear end portions, the inner edge of said strip along said intermediate shoulder engaging portion being longer than the outer edge whereby said front and rear end portions extend straight downwardly from said intermediate portion, with their lower surfaces substantially opposite and parallel to each other and said intermediate portion is transversely inclined downwardly from its inner to its outer edges.
